DESIGN FOR A LAMP HOUSE FOR PROJECTORS

Gustave Fassin, Irondequoit, N. Y., assignor to
Bausch & Lomb Optical Company, Rochester,
N. Y., a corporation of New York

Application September 14, 1933. Serial No. 49,255

Term of patent 14 years

To all whom it may concern:

Be it known that I, GUSTAVE FASSIN, a subject
of the King of Belgium and a resident of the town
of Irondequoit, county of Monroe and State of
New York, have invented a new, original, and
ornamental Design for Lamp House for Projectors,
of which the following is a specification,
reference being had to the accompanying drawing,
forming a part thereof.

The figure is a perspective view of a lamp house
for projectors, showing my new design.

I claim:

The ornamental design for a lamp house for
projectors substantially as shown.

GUSTAVE FASSIN.
